UNITED STATES PATENT OFFICE.

GEORGES HUILLIER, OF PARIS, FRANCE.

WIND-SHIELD FOR VEHICLES.

No. 849,242.

Specification of Letters Patent.

Patented April 2, 1907.

Application filed May 22, 1906. Serial No. 318,247.

To all whom it may concern:

Be it known that I, GEORGES HUILLIER, a citizen of France, residing at Paris, in the said Republic, have invented new and useful 5 Improvements in Wind-Shields for Vehicles, (for which I have obtained a patent in France, No. 355,485, bearing date June 23, 1905, to which is attached a patent of addition, No. 5,511, of November 28, 1905; in 10 Great Britain, No. 19,135, September 21, 1905; in Belgium, No. 188,541, of December, 1905, and in Spain, No. 37,276, of January 24, 1906,) of which the following is a specification.

15 This invention has for its object an arrangement of wind or weather shield applicable for all vehicles, and more particularly for motor-cars.

It comprises a very light glazed frame supported so as to be placed near the eyes of the 20 driver or the passengers, or at least at a short distance from them, and is held either by the vehicle itself or by means of two dismountable tubular uprights adapted to be fixed to 25 the splash-board by means of sockets, this glazed frame being preferably suspended in an inclined position, so as to retain during 30 the running of the car a slight oscillatory movement, the arrangement being completed by a protective curtain which is fixed, on the one hand, to the lower part of the frame and, on the other hand, to the splash-board.

A wind-shield arranged in accordance with the present invention is shown in the accompanying drawings as an example, Figure 1 35 being a view in lateral elevation; Fig. 2, a front elevation view with a part removed.

In the drawings the same reference-letters indicate the same parts in the two figures.

40 The apparatus comprises two uprights *b*, made of tube, fixed to the splash-board *a* of the vehicle by means of sockets *f*, themselves attached to this splash-board and in which 45 they slidably fit, thus rendering the whole arrangement dismountable. To the upper ends of the uprights *b* a very light glazed frame *c* is fixed by means of supports *g*. The axis of this frame is placed at the level of the 50 line of vision, and the frame may even be arranged with its upper part sloping forward, as shown by the dotted line in Fig. 1.

55 *d* is a curtain of thin cloth or other suitable material, by means of which the wind-shield is completed at the point where it is unnecessary to have a transparent body or

substance. This curtain is attached, on the one hand, to the glazed frame by small copper turn-buttons *h* and, on the other hand, to the splash-board by grooved nails *l* or the like. 60 Two small straps *e*, placed on each side and at the bottom of the curtain, hold it in the direction of its width.

The result of this method of construction just described is that the apparatus herein-before described is very easily dismounted, and consequently easily separated from the vehicle when it is no longer necessary. In order to do this, it suffices to withdraw the tubes *b* from their sockets *f* after having first 70 separated the curtain *d* from the frame *c*.

It is quite evident that the method of attachment which has just been described may be varied in the direction that in vehicles having a projecting hood, for instance, the 75 glazed frame may be easily attached to the projection of the hood itself, and thus the suspension-bars be dispensed with. What is mainly important is essentially that the glazed frame shall be placed sufficiently near 80 the driver or the passengers, which is as well obtained by means of the suspension-rods as by any other means of attachment. The position of the glass near the eyes of the driver or the passengers, or at least at a small 85 distance from them, (about forty centimeters from the face,) allows of the latter having a much clearer view of objects than if this glass was farther away. It also increases the field 90 of vision comprised in the interior of the frame of the glass, which causes this frame no longer to be an obstacle to the view as in the ordinary glazed frames. It also allows of the disagreeable drafts arising from the current of air to be avoided, because in this case 95 the drafts pass behind the driver without affecting the face, which is completely protected by the wind-shield. It is quite evident that the glass constituting the wind-shield in no way needs to oscillate in order to 100 obtain the result hereinbefore specified.

Thus, if desired, it may be made rigid either by the method of attachment itself or by locking the nuts at the point where they are hinged; but the result of the fact that the 105 glass may oscillate has the advantage, on the one hand, that it may be inclined, allowing the travelers easy access, while, on the other hand, always preserving a slight oscillatory movement it results that when it rains water 110 never clings to the glass, but, on the contrary, mostly runs off, thus allowing a clear view,

which is particularly appreciable in case of bad weather.

I declare that what I claim is—

A wind-shield for vehicles, comprising two uprights having their tops curved inwardly, means for detachably holding the uprights to the splash-board, a glazed frame hinged at its upper end to said uprights, so as to freely oscillate, and a curtain having its upper end detachably secured to the lower end

of the glazed frame, so as to oscillate with the latter and its lower end detachably secured to the splash-board.

In testimony whereof I have signed my name to this specification in the presence of 15 two subscribing witnesses.

GEORGES HUILLIER.
